UNITED STATES PATENT OFFICE.

WALTER H. DICKINSON, OF CHESTER, PENNSYLVANIA, ASSIGNOR TO UNITED STEEL BLOCK CORPORATION, OF CHESTER, PENNSYLVANIA, A CORPORATION OF DELAWARE.

LOGGING BLOCK.

Application filed March 5, 1925. Serial No. 13,121.

The object of my invention is to provide a detachable rope guide for snatch blocks and other types of logging blocks, which comprise essentially a housing enclosing a 5 freely rotatable grooved sheave, and a shackle, the latter being openable to allow a rope to be engaged with the sheave and closable to prevent the escape of the rope from the block.

10 In logging operations, the strain or pull on the rope is often at an angle to the direction of extension of the sheave and may even be parallel to the sheave's axis. The space between the shackle and the periphery of the sheave being necessarily a capacious one, the rope is pulled out of engagement with the sheave, and if the block is badly rigged, or if there is any obstacle to the free swinging of the block into line with the 15 rope, the latter pulls on the side of the housing or slips up into the shackle, so that the block not only fails to function but may be damaged or ruptured.

20 This objection has hitherto been overcome by providing the housing with an integral guard which extends nearly across the housing a short distance from the periphery of the sheave. This construction, however, is objectionable in that a coupling between adjacent sections of rope cannot slip between the guard and the periphery of the sheave. This necessitates unfastening and then opening the shackle, slipping the coupling through the block and closing and re-fastening the shackle. This being impracticable, 25 most loggers use a changing line block and afterward, when lines are changed ready to log, substitute a block with a guard.

30 The object of my invention is to provide a separable guard which is readily removable and insertable and when in place functions as efficiently as an integral guard. Such a block presents distinct advantages over the block provided with an integral guard and 35 moreover has a wider range of use, as it is adapted for use as a universal block for out-hauling purposes as well as a changing line block for overhead skidders. When used in place of a block with an integral guard, the 40 guard may be readily removed to allow a coupling to slip through, and may be readily replaced.

The invention is susceptible of different

embodiments, several of which are shown in the drawings, in which:—

55 Fig. 1 is a side view of part of a snatch block containing one embodiment of my invention.

Fig. 2 is an end view of Fig. 1.

60 Fig. 3 is a view, similar to Fig. 1, of another embodiment of my invention.

Fig. 4 is a view, similar to Figs. 1 and 3, of still another embodiment of my invention.

65 In Figs. 1 and 2: *a, b*, represent the spaced apart side plates of the body or housing of the block, each side being provided with outside webs *c*. The sheave *d* is positioned between the sides *a* and *b* and turns in bearings therein. The shackle *f* is pivoted to one of the sides, *b*. Its free end swings down 70 between projections *e, e* on the other side *a* and is secured in position by means of a pin *i* extending through said projections and the free end of the shackle; all in accordance with a common construction.

75 A guard *g*, formed of a flat plate of steel and bent into the shape of an L, is removably affixed to the block by inserting the longer arm of the L between the upper edge of the side *a* and the rounded movable end of the shackle *f*. Preferably this arm of the guard is long enough to extend entirely across the space between the sides of the block and between the upper edge of the side *b* and the pivoted end of the shackle *f*, so as to hold the rope *r* from slipping entirely away from the sheave. When the guard is inserted to its fullest extent, the short arm of the guard abuts against the side *a* of the block. A cotter pin *h*, or similar retainer, is then inserted through webs *c* so as to extend in front of the short arm of the guard, thereby preventing the guard from becoming dislodged from its operative position.

80 85 It is obvious that by drawing out the cotter pin, the guard may be readily removed, and it may be as readily replaced and then retained in position by reinserting the cotter pin.

90 95 In Fig. 3 is shown a modification wherein the sides are provided with aligning openings, such as a notch or recess *m*, midway between webs *c*, through which is inserted a headed guard pin *n*, which performs the same function as guard plate *g*.

100 105 In Fig. 4, each side plate is provided with

two holes outside webs *c*, each hole in one side plate aligning with one of the holes in the other side plate, and two headed guard pins *p* are inserted, these two pins performing the same function as guard plate *g* or guard pin *n*.

A retainer, such as a cotter pin *o*, should be provided, at the ends thereof opposite their heads, to hold the pins *n* and *p* from displacement from working position.

It is obvious that my inventive conception may be embodied in other mechanical forms.

What I claim is:

1. A pulley block having a shackle, a sheave rotatably mounted in the housing of the block, and a separable stationary rope guard independent of the block structure adapted to be inserted in the space between the sheave and the shackle while the block

20 is under tension and which is readily removable from operative position while the block is under tension to allow the passage of a coupling through said space.

2. A pulley block having a shackle, a sheave rotatably mounted in the housing of the block, a separable stationary rope guard independent of the block structure adapted to be inserted in the space between the sheave and the shackle while the block is under tension and which is readily removable from operative position while the block is under tension to allow the passage of a coupling through said space, and a retainer to hold the guard from accidental displacement.

3. A pulley block comprising a housing having sides, a shackle pivotally connected to said sides, a sheave rotatably mounted in the housing between the sides, there being sufficient space between the sheave and

shackle for the passage of a coupling, there being guard receiving recesses in the sides of the housing between the sheave and shackle, and a removable stationary rope guard secured in said recesses independent 45 of the block structure and arranged to be removed or inserted while the block and rope on the sheave are under tension.

4. A pulley block comprising a housing formed of side plates, a sheave rotatable between, and on an axis substantially at right angles to the side plates, an arch-shaped shackle pivotally secured to one side plate and adapted to swing toward the other side plate and form, with the housing and sheave, a spacious space, means to secure the movable end of the shackle to the last named side plate, and a separable L-shaped guard plate the longer leg of which is insertable between the upper edge of one side plate 60 and one end of the shackle and movable across said space relatively close to the edge of the sheave until its end extends between the upper edge of the other side plate and the other end of the shackle and its shorter 65 leg abuts against the outside of the first side plate.

5. A pulley block in accordance with claim 4 in which the housing is provided with webs on the outside of the side plates, and a cotter pin insertable through said webs so as to extend outside the short leg of the L-shaped guard plate and hold it from displacement when positioned to act as a rope guard.

In testimony of which invention, I have hereunto set my hand, at Marcus Hook, Pa., on this 13th day of February, 1925.

WALTER H. DICKINSON.
